UNITED STATES PATENT OFFICE

FEIBUS KOBAK, OF BROOKLYN, NEW YORK, ASSIGNOR TO THE METRO CHOCOLATE CO.
INC., OF BROOKLYN, NEW YORK, A CORPORATION OF NEW YORK

DESIGN FOR A LOLLYPOP CLUSTER OR SIMILAR ARTICLE

Application filed April 14, 1932. Serial No. 43,490. Term of patent 7 years.

To all whom it may concern:

Be it known that FEIBUS KOBAK, a citizen of the United States, and resident of Brooklyn, in the county of Kings and State of New York, has invented a new, original and ornamental Design for Lollypop Cluster or Similar Article, of which the following is a specification, reference being had to the accompanying drawing, forming part thereof, in which,

Fig. 1 is a plan view of a lollypop cluster embodying my new design; and

Fig. 2 is a perspective view thereof.

I claim:

The ornamental design for a lollypop cluster or similar article, substantially as shown.

Dated, April 9th, 1932.

FEIBUS KOBAK,
